UNITED STATES PATENT OFFICE.

WILLIAM HENRY LAND, OF DES MOINES, IOWA.

IMPROVEMENT IN SHOES.

Specification forming part of Letters Patent No. 173,303, dated February 8, 1876; application filed May 31, 1875.

To all whom it may concern:

Be it known that I, WILLIAM HENRY LAND, of Des Moines, in the county of Polk and State of Iowa, have invented certain Improvements in Shoes, of which the following is a specification:

The object of my invention is to save material and labor in cutting and making a shoe, and also to produce a shoe improved in appearance, usefulness, and durability. It consists in cutting the "upper" in two pieces, so formed relative to each other that straps on the one and lappets on the other will close and fit over the instep neatly and conveniently, as hereinafter fully set forth.

Figure 1 of my drawing is a plan view, illustrating the form of the one piece which makes one complete side, and also the front of the shoe, and the straps that draw across the instep. A is the complete side; B, the front or toe part required for the opposite side. C C is a broken line indicating the center of the complete upper. Nos. 1 and 2 are the straps connected with the side A, and formed thereon by simply cutting out the leather from the spaces marked d d. The broken line f f indicates the form of the second piece required to form the upper complete for a shoe.

Fig. 2 is an outline of the second piece. C is the rear part of one side of a shoe. The broken line g g indicates the lap that will be made when it is joined to the front part B, connected with the complete side A. a b are lappets or ears extending beyond the central line c c, and are in such position relative to the straps, Nos. 1 and 2, on the complete side A that they will aid in closing the front of the shoe neatly and completely over the instep without any surplus of leather, and without sewing on any parts.

Fig. 3 is a perspective view of a complete shoe, and illustrates the relative positions of

the parts A B C when joined as required. 3 and 4 represent buckles attached to the part C, to engage the straps Nos. 1 and 2, extending from the part A. K represents a gore that may be cut from soft leather or cloth, and attached to the parts A and C, to completely close the space between them when the shoe is unbuckled, and to double and fold over the instep when the shoe is buckled.

My form of uppers is especially designed and adapted for "brogans" or "plow-shoes," generally worn by farmers and miners, but may also be advantageously used for finer shoes. They must be cut in pairs to form "rights and lefts," and may vary in size and material, as desired.

I am aware that shoe-uppers have been formed of two pieces, in such a manner as to lap over the instep of the wearer's foot, and that straps or tucks have been integral parts of the uppers; but I claim that my peculiar manner of shaping and cutting the upper in two pieces and goring the portions designed to lap and close upon each other, and thereby forming the straps 1 and 2, and two corresponding flaps or ears, a and b, to close the shoe tightly over the instep without crimping the leather, and without sewing on flaps and tucks, is a new and valuable improvement.

I claim as my invention—

In the manufacture of a shoe or gaiter, the upper composed of the pattern A B, having the straps 1 and 2 cut of one and the same piece of material, in combination with the pattern C, having the flaps a b integral therewith, substantially as and for the purposes specified.

WILLIAM HENRY LAND.
